THREAD END HOLDERS FOR SEWING MACHINES
 Orland B. Reid, Union, N.J., assignor to The Singer
 Manufacturing Company, Elizabeth, N.J., a corpora-
 tion of New Jersey
 Filed May 26, 1958, Ser. No. 737,606
 11 Claims. (Cl. 112—253)

The present invention relates to sewing machines and has for an object to provide a new and improved means for holding the ends of the sewing threads during the initial stitches to prevent unthreading of the needle.

Upon the completion of a sewing operation on a sewing machine, the completed workpiece remains tied to the machine by the sewing threads which must be severed in order to remove the workpiece from the machine. When the sewing threads are severed, there results the loose ends which, if they are long enough, will accommodate initiation of the next sewing operation without unthreading the needle. However, long thread ends at the beginning as well as at the end of a seam on the workpiece are undesirable since in the finished garment they are unsightly and must therefore be trimmed, and also, since any thread ends constitutes wasted thread. To economize on thread and at the same time eliminate the subsequent trimming operation, the thread chain should be trimmed as close as possible to the workpiece and to the point of stitch formation, thus minimizing the length of the thread ends. In accordance with the present invention there is provided means for holding the loose end of the sewing threads at the beginning of the sewing operation, thus permitting relatively short thread ends without unthreading the needle. As soon as the threads are secured to the workpiece by the formation of a stitch or two, the thread ends are released to permit feeding of the work.

It is an object of this invention to provide a thread end holder that is efficient, reliable, durable and relatively economical to produce. It is a further object of this invention to provide a thread end holder that is designed to be used in a cyclically operated sewing machine, which can be readily actuated automatically in timed relation to the actuation of the sewing machine, and which is so constructed and arranged that it will not interfere with the manipulation of the work on the bed plate of the machine.

A further object of this invention is to provide a thread end holder that will position and hold the bobbin thread to prevent improper positioning thereof.

In the accompanying drawings;

FIG. 1 is a fragmentary view, in elevation, of the head end of a sewing machine embodying the present invention,

FIG. 2 is a fragmentary head end view, partly in elevation and partly in section, of the sewing machine illustrated in FIG. 1,

FIG. 3 is a detail vertical sectional view through the point of stitch formation of the sewing machine of FIG. 1,

FIG. 4 is a fragmentary horizontal sectional view above the throat plate of the sewing machine of FIG. 1.

The present invention in herein disclosed as embodied in the automatic cuff sewing machine that forms the subject matter of copending application Serial No. 737,775, filed May 26, 1958, to which reference may be had for a more complete understanding of the machine. The automatic cuff sewing machine is herein disclosed only insofar as is necessary to obtain a full understanding of the present invention.

With reference to the drawings there is disclosed a sewing machine 1 mounted upon a table 2 and having a bed including a bed plate 3, the upper surface of which com-

prises the work supporting surface of the machine, and a bracket arm 4 terminating in a head 5 overhanging the bed plate 3. A needle bar 6 is mounted in the head 5 for vertical endwise reciprocation and at its lower end carries a needle 7 that cooperates with a rotary hook 8 journaled in the bed of the machine in the formation of two-thread lock stitches by the concatenation of a needle thread 9 threaded through the eye of the needle 7 and a bobbin thread 10 that emerges from the bobbin case 11 carried by the rotary hook 8. About the point of stitch formation, the bed plate 3 is provided with a throat plate 12 having a needle aperture 13 through which the needle 7 passes during stitch formation. Also mounted vertically in the head 5 for endwise reciprocation is a presser bar 14 carrying a presser foot 15 at its lower end for holding the work down against the throat plate 12, the presser foot 15 having a needle hole 16 in alignment with the needle aperture 13 in the throat plate 12 and through which the needle 7 also passes during stitch formation.

The thread end holder is carried by a mounting plate 17 secured as by screws 18 to the face plate 19 that closes the open end of the head 5. Mounted on the upper portion of the plate 17, is a cylinder 20 having an internal cylindrical piston chamber 21. The open bottom of the piston chamber 21 is closed by a cylinder head 22 secured to the cylinder 20 by screws 23 that are threaded into lugs 24 on opposite sides of the cylinder 20.

Within the piston chamber 21 there is disposed a piston 25 mounted upon the end portion 26 of a two-part piston rod 27 that extends downwardly through the cylinder head 22 and is mounted for endwise sliding movement in a bushing 28 on the cylinder head 22. The lower portion 29 of the rod 27 is reduced and is guided by a bracket 30 mounted on the lower end of the plate 17 by screws 31 and having an apertured ear 32 through which the rod extends. For guiding the rod 27 to prevent it from turning, there is mounted on the lower portion 29 a collar 33 having a laterally extending arm 34 that projects through a slot 35 in the mounting plate 17. A coil compression spring 36 is disposed in the piston chamber 21 between the piston 25 and the cylinder head 22 to bias the piston upwardly. For forcing the piston 25 downwardly and thereby depressing the rod 27, the upper end of the piston chamber 21 above the piston 25 is connected by a tube 37 to a solenoid-actuated valve unit 38 mounted upon the underside of the table 2. The unit 38 is connected by a tube 39 to a source of compressed air and includes an air valve that will lead compressed air from the tube 39 into the tube 37 when the solenoid is energized by power supplied through the wire 40.

Upon the lower end of the rod 27 there is mounted a clamping foot 41 having a rearwardly extending cylindrical stud 42 mounted on a horizontal axis in a bore in a mounting shank 43 that in turn has a bore into which the lower end 29 of the rod 27 extends and in which it is secured by a set screw 44. The clamping foot 41 is thus free to turn about a horizontal axis to provide for automatic leveling of the foot 41 relatively to the throat plate 12. Turning of the foot 41 is limited by a pin 45 on the stud 42 that is received in a groove 46 in the shank 43. To insure a secure clamping by the foot 41 of the loose ends of the threads 9 and 10, which are designated 47 and 48 respectively, the throat plate 12 is provided with a roughened surface 49 in the area engaged by the foot 41.

To position the thread ends 47 and 48 under the clamping foot 41 there is provided a blower comprising a bore or nozzle 50 in the throat plate 12 that is arranged at such an angle that the air emerging therefrom will carry the thread ends under the foot 41. The bore 50 com-

municates with a nipple 51 mounted on the underside of the throat plate 12 and connected by a tube 52 with a source of compressed air.

To prevent breaking the needle thread 9 while the end 49 thereof is clamped by the foot 41 and when there is not sufficient thread in the thread system of the machine to accommodate the take-up action, there is provided an arm 53 pivotally mounted on the bracket 54 and having an end engaged by the collar 33 when the clamping foot 41 is lowered. The other end of the arm 53 extends around the head 5 to engage and release the needle thread tension device as shown in FIG. 2.

In the operation of the present thread end holder, the thread ends are blown under the clamping foot 41 by the air emerging from the nozzle 50. Before the operation of the sewing machine 1 is initiated, the solenoid of the valve unit 38 is energized from a control mechanism through the wire 40 to conduct compressed air from the tube 39 to the tube 37 and thus to the piston chamber 21 above the piston 25 to force the piston and the piston rod 27 downwardly against the action of the spring 36. As the piston rod 27 moves downwardly, the clamping foot 41 which is carried by it is forced downwardly against the throat plate 12. The clamping foot 41 is held down only until the threads are locked in the work by the formation of a few stitches. The thread ends are then released by deenergization of the solenoid of the valve unit 38, which closes the supply of air pressure to the tube 37, thereby permitting the spring 36 to raise the piston 25 and thus lift the clamping foot 41.

In the illustrated machine, at the initiation of the sewing cycle, the direction of feed is in the direction of the arrow A in FIG. 4 and the work is arranged to the right of the point of stitch formation which is defined by the needle 7, or in other words, coincides with the needle aperture 13 in the throat plate 12. To insure that the clamping foot 41 does not engage the work and also to insure that the thread ends 47 and 48 will not be stitched down to the work by the subsequent stitching, the clamping foot 41 is arranged laterally of the direction of feed on the opposite side of the point of stitch formation from the work. With the thread ends thus held to the side opposite from the work, the needle will descend on the right side of thread ends. At the same time, to permit feeding of the work relatively to the point of stitch formation while the thread ends are clamped, the nozzle 50 is arranged to blow the thread ends slightly forwardly relatively to the direction of feed. Thus, as the work is fed in the direction of the arrow A, the thread ends will in effect pivot about the point at which they are clamped and will not be tensioned and thereby pull the work.

Another feature of this arrangement in which the thread ends are arranged laterally of the direction of feed is that with the work advancing in the direction of the arrow A, the blower will be effective until just immediately before the beginning of the stitching operation. This is important in a cyclically operated sewing machine as disclosed for example in the above noted application Serial No. 737,775, wherein the work is carried by a traversing mechanism including an arm as illustrated at 55 in FIG. 1 which carries it relatively to the point of stitch formation to produce a seam of a predetermined configuration as defined by the cycle of actuation imparted to the arm 55. In order to define a complete cycle there is an idle stroke during which the arm 55 must pass across the point of stitch formation, at which time the sewing machine 1 is out of operation with the needle 7 raised and the presser foot 15 and the clamping foot 41 are raised. In the particular machine illustrated, this idle stroke occurs at the beginning of the cycle with the work moving in the direction of the arrow B in FIG. 4. At the end of the idle stroke, the work immediately begins to move in the direction of the arrow A, the presser foot 15 is lowered, and the operation of the sewing machine 1

is initiated. At this time, the clamping foot 41 must be down to hold the thread ends. Since the clamping foot 41 must be raised while arm 55 is passing under it, it cannot be lowered until only immediately before the sewing operation begins. Thus, the construction and arrangement of the thread end holder in accordance with the present invention does not include any obstructions which would impede the motion of the arm 55 across the point of stitch formation, and, at the same time, provides for operation of the thread end holder immediately before initiation of the sewing operation so that the thread ends will be properly and securely held until the initial stitches are formed.

Having thus described the nature of the invention, what I claim herein is:

- 15 1. In a sewing machine having a frame including a work supporting surface and a head overhanging said work supporting surface, stitching mechanism including a needle bar mounted in said head for endwise reciprocation and carrying at its lower end a needle defining a point of stitch formation on said work supporting surface, a thread end holder for securing the loose ends of the sewing threads during the initial operation of the stitching mechanism comprising a rod carried by said head for endwise movement, a clamping foot mounted upon the lower end of said rod for movement into and out of engagement with said work supporting surface upon endwise movement of said rod for clamping the thread ends against said work supporting surface and fluid pressure means for imparting endwise movement to said rod.
- 20 2. A thread end holder for sewing machines in accordance with claim 1 in which said clamping foot is arranged to engage said work supporting surface laterally of the point of stitch formation relatively to the direction of feed.
- 25 3. A thread end holder for sewing machines in accordance with claim 1 in which said fluid pressure means comprises a piston chamber, a piston mounted in said chamber and operatively connected to said rod, means for conducting fluid pressure into said piston chamber on one side of said piston to force said rod toward said work supporting surface, and spring means operatively connected to said rod for biasing the same in the direction away from said work supporting surface.
- 30 4. A thread end holder for sewing machines in accordance with claim 3 in which said fluid pressure means is pneumatic and in which said means for conducting fluid pressure into said piston chamber comprises a source of pneumatic pressure, an air valve operatively connected at one side to said source of pneumatic pressure and at the other side to said piston chamber for selectively introducing pneumatic pressure from said source to said piston chamber.
- 35 5. A thread end holder for sewing machines in accordance with claim 4 in which said air valve is solenoid actuated.
- 40 6. A thread end holder for sewing machines in accordance with claim 1 in which said clamping foot is pivotally mounted on said rod on an axis parallel to said work supporting surface to provide for automatic leveling of said clamping foot relative to said work supporting surface.
- 45 7. A thread end holder for sewing machines in accordance with claim 6 in which said rod has a shank to which said clamping foot is pivotally mounted and in which the pivotal connection comprises a stud on said clamping foot and journaled in a bore in said shank, and means for limiting turning of said stud comprising a pin extending through said stud, said shank having a groove for receiving said pin and providing for limited turning of said pin therein.
- 50 8. A thread end holder for sewing machines in accordance with claim 1 having means for positioning the loose thread ends beneath said work clamping foot comprising
- 55 75

a source of compressed air and a nozzle for directing a stream of air across said point of stitch formation and beneath said clamping foot.

9. A thread end holder for sewing machines in accordance with claim 8 in which said nozzle emerges from beneath said work supporting surface.

10. In a sewing machine having a work supporting surface and stitching mechanism for defining a point of stitch formation on said work supporting surface, a thread end holder for securing the loose ends of the sewing threads during the initial operation of said stitching mechanism comprising a clamping foot, means mounting said clamping foot for movement into and out of engagement with said work supporting surface for clamping the thread ends against said work supporting surface, air pressure actuated means for moving said clamping foot into thread end clamping engagement with said work supporting surface, and means for positioning the loose thread ends beneath said work clamping foot comprising a nozzle for directing a stream of air across said point of stitch formation and beneath said clamping foot. 15

11. In a sewing machine having a frame including a bed plate and a head overhanging said bed plate, said bed plate having a separable throat plate disposed beneath said head and the upper surface of which together with the upper surface of said bed plate comprise a work 20 25

supporting surface, said throat plate having a needle aperture, stitching mechanism including a needle bar mounted in said head for endwise reciprocation and carrying at its lower end a needle that penetrates said throat plate through said needle aperture during stitch formation and thereby defines a point of stitch formation on said throat plate, and means for positioning the loose ends of the sewing threads on said throat plate comprising a nozzle formed in said throat plate and emerging on the work supporting surface thereof at a point spaced from said point of stitch formation, said nozzle being arranged to direct a stream of air across said point of stitch formation, and means on the underside of said throat plate for connecting said nozzle to a source of air pressure.
